UNITED STATES PATENT OFFICE.

PHILIP MUELLER AND ANTON C. SCHUERMANN, OF DECATUR, ILLINOIS, ASSIGNEES
TO ADOLPH MUELLER, OF DECATUR, ILLINOIS, TRUSTEE.

ADJUSTABLE LAVATORY COMBINATION FIXTURE.

Application filed November 12, 1919. Serial No. 337,496.

To all whom it may concern:

Be it known that PHILIP MUELLER and ANTON C. SCHUERMANN, citizens of the United States, residing at Decatur, in the county of Macon and State of Illinois, have invented new and useful Improvements in Adjustable Lavatory Combination Fixtures, of which the following is a specification.

This invention relates to combination fixtures for lavatories and analogous devices.

Combination fixtures for lavatories comprise, generally stated, the hot and cold water connections from suitable supply pipes, delivering, in modern plumbing, through a common supply spout or faucet, but separately controlled; such independent controlling devices or stop cocks for the hot and cold water; and a bowl waste, with or without a waste overflow, with waste controlling means. Such fixtures are of metal and are fitted to lavatory bowls and slabs by the plumber in installing the plumbing. It has been necessary, in the art of fitting up lavatories as now practiced, to make fixtures and fittings for the particular bowl and slab with which they are used so as to permit proper and ready installation, and variations in styles of bowls and slabs with respect to dimensions, spacing of fixture holes, thickness of bowl walls, and the like, have necessitated, to a considerable extent, the making of fixtures for each particular style or variation in bowl and slab.

The present development is intended to overcome this difficulty and provide a lavatory combination which is adaptable to bowls of various styles and dimensions within a wide range. This result is accomplished by providing faucet and waste connections and mountings which permit great flexibility in the matter of placing them, both with relation to one another and with relation to the holes or passages through the vitreous or other ware of which the bowls and slabs are ordinarily formed. As a result of our invention a fixture is provided which may be adapted by the plumber to a wide range of lavatories, and the necessity of special fittings for different installations is largely done away with.

In the drawings herewith, illustrating embodiments of our invention—

Figure 1 is a view in central vertical sec-

tion of a bowl equipped with a fixture made in accordance with our invention.

Figure 2 is a view in vertical section on substantially the line 2—2 of Fig. 1, looking in the direction of the arrow.

Figure 3 is a view in vertical section, on an enlarged scale, of the water supply connections and the supply spout or faucet.

Figure 4 is a bottom plan view, parts being in section, of portions of the bowl, slab and fixtures.

Figure 5 is a horizontal sectional view on substantially the line 5—5, Fig. 1, looking in the direction of the arrow, to show the waste stop and its actuating yoke.

Figure 6 is a detail view in vertical section of the waste stop and yoke, on the line 6—6 of Figure 5.

Figure 7 is a central vertical section of a slightly different form of the invention.

In the drawings, in the several figures of which like parts are indicated by like reference characters, 10 designates a bowl, of any suitable material, design, and dimensions, the usual bowl slab 11 and back slab 12 being shown.

In the present case it is shown as of vitreous ware and as having walls of considerable thickness, but it will be understood that it may be varied as to material, dimensions, and design, as the bowl proper forms no part of our invention and the fixture devised by us may be adapted to different bowls.

The said bowl 10 has a waste-outlet provided with a fitting 13, and may be provided with an overflow 14 leading to the waste passage below the outlet 13, although such overflow may be omitted if desired, and in some types of bowls, as, for example, those formed of relatively thin enamelled iron, is not present, without affecting the application of our novel fixture to the bowl.

In the rear of the bowl slab 11 are the holes for receiving the fittings, in the present case three in number, two of which openings, 15, are for the mounting of the stop cocks 16 and their associated parts, and the third, 17, of which, is for the mounting of the supply spout or faucet 18 and its associated parts. These holes, in different slabs, may vary in number; their relative positions; and may be differently spaced from one another.

Mounted in each of the holes 15 are the hot and cold stop cocks which are similar in construction and comprise the coupling member 19, to the lower end of which is secured the valve body 20 connecting with the supply pipe 21 and having any suitable valve seat, which is controlled by any suitable valve, as the valve 22, which, in the present instance, is shown as of the quick compression type. The valve stem 23 extends upwardly through the coupling member 19, which coupling is secured to the slab 11 in any suitable manner so that the coupling and associated parts will be supported from the slab, the valve stem terminating in an operating handle 24 and having an ornamental finishing fitting 25 about its upper end and surrounding the stuffing box 26 through which the stem passes, and those other fittings which project above the slab.

To the cock bodies 20 are secured by a slip joint connection 27, the supply pipes 28, these supply pipes being bent at their ends 25 so as to engage by a slip joint coupling 29 in connections 30 these connections 30 being mounted, as best known in Fig. 2, so as to have a *swiveling* action relative to each other and relative to the shank of the supply spout 18.

The shank 33 of the supply spout is fastened in any suitable manner, as by the lock plate 31 and nut 32, so as to clamp the supply spout 18 firmly to the slab 11, and the swiveling connections 30 are clamped to each other and to the lower end of the shank 33 by a nut 34 engaging a tube 35, the upper end of which is threaded or otherwise secured in the neck of the spout casing 36, as shown in Figs. 1, 2, and 3. If desired, stay lugs 36^a may be provided at one or more points in the fitting to support the tube 35 against side strains.

It will be seen that the swiveling connections 30 are provided with seats 37, where they engage each other and the shank 33 of the supply spout, these seats being packed so as to give a fluid tight joint and being held in fixed position by the packed joint 50 clamping nut 34, heretofore referred to, this clamping nut having, preferably, a friction ring 38 which *engages* a rod 39 traversing the tube 35 and provided at its upper end with an operating handle 40 for controlling 55 the waste stopper 41.

No claim is made in this application to the independent development relating to the control means for the waste stopper, the instant case being directed to the other features of the fitting.

With this arrangement it will be seen that a considerable range of adjustment is provided for to meet conditions imposed by differently designed slabs or supports. The 65 *swiveling* connections 30 may, of course, be

swung to various angles so as to be adjusted to differently positioned cocks, for if the valve openings in the slab be nearer to or farther from the central opening for the supply spout, these connections 30 will 70 be adjusted accordingly and the slip joint supply connections 28 will accommodate themselves to the different angular portions of the swiveling connections 30. By furnishing these slip joint supply connections 75 28 of maximum length, the plumber installing the fixtures can take care of a maximum spread or distance apart of the cock-receiving openings in the slab or support and he can also take care of cock openings 80 in the support which are closer together, by swinging the arms 30 toward or from each other. If a close adjustment is necessary, the straight end of the supply connection 28 may be cut to the proper length and such 85 supply connection be brought very readily to fit a close coupled or assembled set of fittings, thus giving great flexibility in the matter of installing these fixtures. Furthermore, the slip-joint union of the upturned 90 end of the connection 28 admits of a considerable adjustment vertically of the parts to meet varying conditions.

The operating rod 39 for the waste stopper 41 is threaded at its lower end, preferably in the manner shown in Fig. 1, into an L-shaped member 42, the other arm of which carries a pin 40' adjustably mounted therein, which engages a vertically disposed lifter rod 43 passing through a stuffing-box 100 44 into the waste stopper casing 45, the lower end of the lifter rod 43 passing through an aperture in a guiding lug 46 on the waste casing to steady and guide its movements. Adjustably mounted on the 105 lifter rod 43 is a fork 47, which straddles the lower end of the waste stopper 41. The stopper 41, at its lower end, is grooved at 48 and flattened on opposite sides 49, as shown in Fig. 5, so as to permit disengagement of 110 the parts by turning the waste stopper until the flattened portions 49 register with the fork 47, whereupon the waste stopper may be withdrawn. In order that the waste stopper 41 may be locked in place against 115 accidental removal, it is preferably slotted at 50, as shown in Fig. 1, which slot is engaged by a screw 51 threaded in the wall of the casing 45, the slot being of sufficient length to permit the stopper to be raised 120 and lowered through the lifting devices just described.

In order that this waste operating assembly just described may be fitted to basins of different thickness, the casing 45 is 125 threaded at its upper end to the waste outlet pipe 13, which is threaded throughout the greater part of its length, there being a suitably packed joint between the top of the casing and the bottom of the bowl, as 130

shown in Fig. 1. To adapt the device to bowls of different thicknesses, the casing 45 and the waste outlet 13 will simply be screwed together to meet the particular dimensions of the bowl, and the lifter rod 43, its fork 47 and the operating connections with the lifter rod 39 will be adjusted to meet these different conditions. By this construction, the waste fitting can be adapted to a great variety of bowls of different thicknesses, and bowls in which the waste outlet is differently positioned with respect to the faucet or spout holes in the slab, for it will be seen that the pin 40' is adjustably mounted in the L-shaped member 39 so that it may be elongated or shortened to take care of different spacings of the hole for the waste in the bowl and the hole for the supply spout in the slab.

In that form of the invention disclosed in Fig. 7, the construction is generally, the same as that heretofore described. The hot and cold water cocks 52 are arranged similarly to that construction heretofore described, and the supply spout 53 and the waste 54 and waste connections are all identical with the form just discussed. Instead of providing the two swiveling elbows, however, as in the forms heretofore set forth, we have provided a double arm swiveling connection 55, as shown, which is coupled to the shank of the supply spout 53 in a similar manner to that in which the independently swiveling elbow connections are connected, namely, by pack joints as shown, and by the coupling 50 threaded to the lower end of the tube 57, which traverses the supply spout. The supply connection 58 will couple this double arm elbow with the cock bodies on either side in exactly the same manner as that heretofore disclosed.

With this construction it will be observed that while the elbows are not independently adjustable angularly, the whole coupling can be turned angularly about the faucet shank so that the ends of the elbow coupling 55 can be variously positioned to take care of differences in the spacing of the members of the combination as great flexibility is provided by this form which permits the swinging or angular adjustment of the double arm elbow axially about the supply spout.

While we have shown a specific embodiment of our invention, it will be understood that this is merely illustrative and in no sense restrictive, for the construction may be varied as to mechanical details without departing from the spirit of our invention.

We claim:

1. The combination, in a fitting of the class described, of a supply spout, supply cocks in fixed relation to said spout, independently swivelled supply elbows fitted to

said spout shank and to each other for angular adjustment, means for holding said elbows in adjusted position, and adjustable connections between said cocks and said elbows.

2. The combination, in a fitting of the class described, of a supply spout, supply cocks in fixed relation to said spout, independent supply elbows fitted to and angularly adjustable with respect to said spout and each other, means for holding said elbows in adjusted position, and substantially L-shaped supply connections between said spout and cocks and vertically and horizontally adjustable relative thereto.

3. The combination, in a fitting of the class described, of a supply spout, a plurality of supply elbows fitted to the lower end of said spout and to each other and angularly adjustable relative to said spout and to each other, a coupling member connected at its upper end to said spout and traversing said spout and elbows, and means at the lower end of said coupling member to clamp said elbows and spout in any desired position of adjustment.

4. A swiveling supply connection for fittings of the class described, comprising a body portion having a waterway therethrough, an annular seat in the end of said body portion surrounding said waterway, and laterally disposed branch connections extending from the body portion, said connections being independently swivelled to said body.

5. A swiveling supply connection for fittings of the class described, comprising a body portion having a waterway therethrough, annular swiveling seats in the ends of said body portion surrounding said waterway, and laterally disposed branch connections extending from the body portion, said connection being independently swivelled to said body and in communication with the waterway therethrough.

6. In a fitting of the class described, the combination of a supply spout having a basin outlet and a shank, a plurality of independent supply elbows swiveled to the lower end of the spout and to each other for independent angular adjustment, a coupling member engaging at its upper end the body of said supply spout and depending through said shank and supply elbows, and clamping means secured to the lower end of said coupling member to clamp said spout and supply elbows in any desired position of adjustment.

In testimony whereof we have hereunto set our hands.

PHILIP MUELLER.
ANTON C. SCHUERMANN.
